F. W. LEONHARD.
GUARD GATE FOR FLOOR OR SIDEWALK DOORS.
APPLICATION FILED OCT. 1, 1914.

Patented Mar. 14, 1916.

UNITED STATES PATENT OFFICE.

FREDERICK W. LEONHARD, OF BUFFALO, NEW YORK.

GUARD-GATE FOR FLOOR OR SIDEWALK DOORS.

1,174,999.

Specification of Letters Patent.

Patented Mar. 14, 1916.

Original application filed July 17, 1913, Serial No. 779,501. Divided and this application filed October 1, 1914. Serial No. 864,429.

To all whom it may concern:

Be it known that I, FREDERICK W. LEONHARD, a citizen of the United States, residing at Buffalo, in the county of Erie and State 5 of New York, have invented new and useful Improvements in Guard-Gates for Floor or Sidewalk Doors, of which the following is a specification.

This invention relates to a trap door for 10 sidewalks, floors or similar purposes and has the object to provide such doors with improved automatic guard gates to protect the opening or well and to permit said gates to swing out of the way to give access to the 15 opening when desired.

This application is a division of an application on which Letters Patent were granted to myself November 3, 1914, #1,115,554.

In the accompanying drawings: Figure 1 20 is a longitudinal sectional elevation of a door embodying my improvements, the left half of the same in full lines being in a closed position and the right half in full lines in an open position. Fig. 2 is a vertical cross section of the door well showing the door in its fully open position. Fig. 3 is a plan of the door corresponding to Fig. 1, but showing parts of the sidewalk or floor removed. Fig. 4 is a cross section of the 30 spring joint for one of the guard gate braces the section being taken in line 4-4, Fig. 5. Fig. 5 is a top view of the spring joint.

Similar characters of reference indicate corresponding parts throughout the several 35 views.

In its general construction the door, as shown in the drawings, comprises two door leaves A, two longitudinal counter-balanced supporting beams or levers B, B for each 40 leaf connected at their front ends with the underside of the respective leaf at the side edges of the same, hinges C for pivotally connecting the central parts of said beams with the underside of the floor and a counter weight D connected with the rear end of each beam.

41 represents the floor or sidewalk over the vault which may be constructed in any suitable manner and which contains an 50 opening or well.

As a whole the automatic gates embodying my invention are represented by the reference characters F, F and the same are constructed as follows: Each of these gates is 55 composed of flat iron bars riveted in the

shape of a Warren truss and is hinged at its heel to clip angles 23 on the load arm or forward arm of the supporting beams B so as to swing through the same vertical arc with the door and is also capable of swinging 60 transversely relatively thereto. The top and bottom chords 30, 31 of the gates on one leaf are of such length that these gates swing within a circle whose radius is slightly less than the distance from the hinge pin of this 65 leaf to the toe of the opposite leaf so as to give a slight clearance therebetween. This permits one leaf to be fully opened by disconnecting the chains f between the opposing gates without disturbing the other leaf. 70 It also permits the two door leaves to be closed at the same time without interference from the gates.

At the junction of the top chord 30 and the outer web member 32 of each gate the 75 connection with the chains f is made by means of a tie bolt 320, as shown in Fig. 1, or in any other suitable manner. To this tie bolt the chain f is attached which thus gives a flexible connection between the companion gates of the opposite leaves both when the door is closed or open or in any intermediate position. Each of these gates is held laterally by an iron brace preferably composed of two bar sections 33, 33^a having their extremities hinged to the top chord 30 and to the clip angles 23^a which latter is riveted to the underside of the central bar 5 of the respective door leaf. The opposing ends of the brace sections are connected by a flexible spring joint so that the gate may be folded flat on the leaf when the door is open after disconnecting chain f thus giving access to the well opening. This 80 spring joint preferably comprises a pivot 95 pin or rivet 34 connecting the opposing ends of the brace sections 33, 33^a and a spring finger 34^b being an extension of the brace section 33 toward the brace section 33^a and provided with an abrupt stop 34^b and a rivet 100 head or wedge-shaped projection 34^c adapted to engage with opposite sides of the brace section 33^a, while this brace is straightened. For folding this brace its members are turned in a direction for moving the stop 105 34^b away from the section 33^a and carrying the wedge projection 34^c underneath the same. The advantage of this is that in breaking the joint the upper bar passes over the lower bar and rivet head 34^c which tends 110

to spring that portion of the lower bar forming the finger, thus offering the necessary resistance to keep the joint rigid for all axial forces but the joint may be easily broken by a lateral force intentionally applied by the hand on the same side of the brace member on which the rivet head 34° is arranged. In other words, the joint is held rigid on one side from axial forces by a couple of which the rivet connection is one force and the comparatively flat projection 34° in conjunction with the spring resistance of the finger portion of the lower bar forms the second force of the couple. If before closing the door, unfolding of the gates F has been neglected the latter will fall by gravity into an unfolded position when the door is closed and thus be ready to protect the well when the door is reopened. When the gates are closed the two bars forming each brace are slightly longer than a dead center line drawn between the two hinges at opposite ends of the brace, thus allowing the flexible joint to assume a position slightly beyond or slightly eccentric relatively to this line. This eccentricity brings the spring joint members above mentioned into play and any force which tends to open the gates inward tends to increase this eccentricity, thus holding the joint rigid.

By extending the horizontal leg of the clip angles 23 which attach the top and bottom cords 30, 31 of the gates to the forward or load arms, so that their hinges are beyond the vertical leg of the forward or load arm angle, the gates F may be swung outward over the sidewalk as well as inward over the well when the door is open, by simply detaching either end of the gate braces.

If desired, only one door leaf and associated parts need be employed in the case of a well of comparatively small area.

Locking means are provided for holding the door leaves in both closed and open positions, these means preferably comprising the two pairs of locking dogs H, H'. The first set of dogs H lock the door in the open position and the second H' lock the same in its closed position. The members of the first set of locking dogs are situated on the outside of the counterbalanced beam and are fastened to the underside of the walk or floor and automatically engage a lug angle h riveted on the outside of the connection piece 20 and can be released from

above by a rope h'. The members H' of the second set of locking dogs are situated on the inside of the counterbalanced beam 60 and are also fastened to the underside of the walk or floor so as to engage the upper flange of the weight arm, as shown in Fig. 1. The last mentioned dogs may also be released by a rope conveniently placed 65 similar to that used in connection with the dogs H or by any other suitable means.

I claim as my invention:

1. The combination of a vertically swinging door, and a guard gate pivotally mounted on the underside of said door, the axis of the gate being at right angles to the axis of the door.

2. The combination of a vertically swinging door adapted to be arranged horizontally when closed and vertically when open, and a gate pivotally mounted on the underside of said door and at right angles to the axis of the door, and said gate being adapted to drop automatically in a pendant position from 80 said door upon closing the latter.

3. The combination of a vertically swinging door, a guard gate pivotally mounted on the underside of said door, the axis of the gate being at right angles to the axis of 85 the door, and a brace for holding said gate at right angles relative to said door.

4. The combination of a vertically swinging door, a guard gate pivotally connected with the underside of said door, and a brace 90 for holding said gate in its operative position relatively to said door and comprising two bar sections having their extremities pivoted to said door and gate while their opposing ends are pivotally connected, and 95 a spring finger arranged on one of said bar sections and provided with a stop and a wedge projection adapted to engage with opposite edges of the other bar section in the straightened position of said bar sections.

5. The combination of two vertically swinging doors arranged side by side and having their axes parallel, gates pivoted at their rear ends to said door and at right 105 angles to the axes of the latter, and a chain connecting the front ends of said gates.

Witness my hand this 29th day of September, 1914.

FREDERICK W. LEONHARD.

Witnesses:

E. GRAHAM,
ANNA HEIGIS.
